UNITED STATES PATENT OFFICE.

GRANT F. DISCHER, OF MILWAUKEE, WISCONSIN, ASSIGNOR TO GARAGE EQUIPMENT MANUFACTURING COMPANY, OF MILWAUKEE, WISCONSIN, A CORPORATION OF WISCONSIN.

DESIGN FOR AN AUTOMOBILE TIRE-SUPPORT.

44,751.

Specification for Design.

Patented Oct. 21, 1913.

Application filed August 3, 1912. Serial No. 713,196. Term of patent 7 years.

To all whom it may concern:

Be it known that I, GRANT F. DISCHER, a citizen of the United States, residing at Milwaukee, in the county of Milwaukee and State of Wisconsin, have invented a new, original, and ornamental Design for Automobile Tire-Supports, of which the following is a specification, reference being had to the accompanying drawing, forming a part thereof.

The figure is a perspective view of an automobile tire support showing my new, original and ornamental design.

I claim:

The ornamental design for an automobile tire support, substantially as shown.

GRANT F. DISCHER.
